CIGARETTE MAKING AND CUTTING MACHINE

William R. Brown and John E. Mailhot,
Toronto, Ontario, Canada

Application December 23, 1950, Serial No. 202,454

1 Claim. (Cl. 146—168)

This invention relates to improvements in hand-operated cigarette-making devices and more particularly to a device for producing a plurality of individual cigarettes simultaneously.

The principal object of the invention is to enable the formation of a plurality of extremely uniform properly packed precise machine made cigarettes simultaneously in a simple and convenient manner.

Another important object is to provide for the cutting of a formed cigarette length into a plurality of precisely cut individual cigarettes by the utilization of the ordinary razor blade, rendering the machine and the replacement of the cutting elements relatively inexpensive.

The principal feature of the invention consists in providing a novel device to receive and cut a formed length into individual cigarettes.

In particular the invention resides in mounting an array of razor blades with their cutting edges presented and providing a slide to convey the cigarette length into the blade edges in a manner to effect severance into the individual lengths.

Another feature of importance consists in arranging the cutting edges of the blades to cut progressively through the cigarette length to gain an extremely precise and clean cut.

Still another feature consists in providing means to conveniently grip the blades and mount same in a manner for ready replacement.

A still further feature consists in providing in conjunction with the cutter device a means for rolling and subsequently depositing the cigarette form in the cutting machine in correct position for cutting.

Still another feature consists in providing a cutter device which may utilize present cigarette-rolling machines to coact therewith to form and deposit the cigarette in correct position to be cut.

These and other objects and features will be apparent from the following description taken in conjunction with the accompanying drawings.

Referring to the drawings, Figure 1 is a perspective view illustrating the invention and showing the cigarette rolling device in position for coaction with the cutting unit.

Figure 2 is a perspective view of the cutting unit of Figure 1 partly broken away for clarity.

Figure 3 is a fragmentary plan view of the cutter mechanism partly broken away.

Figure 4 is an enlarged transverse section taken on the line 4—4 of Figure 1 with the slide in its outermost position.

Figure 5 is a view similar to Figure 4 but with the slide moved inwardly.

Figure 6 is an enlarged part sectional view taken on the line 6—6 of Figure 1 showing a detail of the knife holders.

Figure 7 is an enlarged vertical sectional detail of the clamp taken on the line 7—7 of Figure 6.

Figure 8 is a view similar to Figure 4 but showing a somewhat modified form of cutter mechanism.

2

Figure 9 is a view similar to Figure 8 but showing the slide moved inwardly.

Figure 10 is a fragmentary plan view of the cutter device shown in Figures 8 and 9.

Figure 11 is a perspective detail of the blade-holding mechanism.

With reference to the drawings, the complete cigarette-making unit comprises the rolling or forming component 1 and the cutting component 2. The cutting component 10 comprises a bottom 3 to which is secured the front and side walls 4 and 5, and bridged between the side walls is a longitudinal flat block 6.

The frame defined by the bottom 3 and the walls and the block 6 includes the cutting mechanism to be herein-after described and serves additionally as a base or mount for the rolling component 1 which comprises a long strip of wood 7 and a flat block 8 of appreciable width spaced from the strip 7 by the sides 9 having slots 10 with the metal turned out to form the slots forming the parallel guides 11.

Secured by the metal strip 12 at the top of the strip 7 is a flexible apron 13 which extends in a fold down between the strip 7 and block 8 to form a pocket 14, being secured to the rear edge of the block 8 by the clamping strip 15.

Mounted beneath the apron 13 is a rod 16 adapted to roll in the guides 11 and provided at the ends with the enlarged knurled knobs 17.

In using the device the rod or spindle 16 is rolled back to the position of Figures 4 or 8. The apron 13 is then depressed with the fingers or the end of a pencil into the pocket 14. Tobacco shreds are then laid in the apron loop or pocket in the required quantity to form a cigarette 20.

As will be appreciated from Figures 1 and 2, the length of the strip 7 and block 8 are such as to produce a multiple length cigarette form so that while the diameter required is equivalent to the ordinary cigarette its length, according to the illustration, will be more than five times the length of the ordinary individual cigarette.

Following placing of the tobacco the operator, by rotating the knobs 17 moves the rod or spindle 16 towards the positions of Figures 5 and 9. When the spindle has been rolled sufficiently to form the tobacco into a tight symmetrical cylinder by the rolling action of the apron the operator then places a narrow strip of cigarette paper on the forward flat exposed surface of the apron above the block 8 and by continued rolling of the spindle towards the position of Figures 5 and 9 the tobacco is rolled onto the paper and the paper is formed to fit snugly around the cylindrical packed tobacco as will be well understood.

Before the spindle 16 has been moved its full travel to the position of Figure 5 to cover the strip and complete the cigarette 18 to discharge it from the apron a suitable adhesive is applied, as is well understood in the art.

With reference to Figures 2 to 6, it will be seen that one edge of the bottom 3 is turned upwardly and rearwardly to form a ledge 19 spaced above the bottom, and spaced from this ledge is a longitudinal plate 20 having its upper edge inturned to define an opposing ledge 21, beneath which is arranged an angled bearing block 22.

Slidably supported on the bearing block 22 are a plurality of blocks 23 which are formed with grooves 24 and 25 to receive the ledges 19 and 21 respectively whereby the blocks 23 are constrained to slide in accurate alignment with the ledges.

Secured to the plate 20 centrally of its length is a rod 26 threaded at its outer end 27. A band spring 28 bent into a closed loop has its two ends and central portion threaded on the rod 26 and is engaged by the compression nut 29, which upon being tightened is adapted to force the band against a stop surface 27' to distort and spread

the sides 30 of the spring into engagement with the adjacent blocks 23 spaced on each side thereof to force same in their guideway constituted by the ledges 19 and 21 in opposite directions moving the outermost blocks against the sides 5 which constitute stops for these outermost blocks.

Gripped between each of the blocks 23 is a razor blade 31 forming a cutting element with its shoulders 32 resting on the ledges 19 and 21 and its underside supported on the bearing block 22. The blades 31 are thus securely held by the clamping blocks 23 by tightening of the nut 29 but are instantly releasable for removal by the compression nut.

The blocks 23 are arranged so that the spacing of the knives 31 is uniform and equal to the desired length of the individual cigarette to be formed.

Arranged beneath the longitudinal block 6 on each side wall 5 of the cutting component is a guide 33 of channel form and these guides receive the arms 34 of a slide 35 provided with a series of slots 36 registering with the blades 31, permitting the slide to be advanced from the showing of Figure 4 to the showing of Figure 5.

From the showings of Figures 2 and 4 it will be seen that the bottom of the slide 35 is immediately above the top of the blocks 23, and with the slide in its outer position there is a space or channel the full length of the slide to receive the cigarette form 18 in the plane of the slide to be engaged by its forward edge 37 which is shown slightly concaved and constituting an undercut lip conforming to the peripheral shape of a cigarette form tending to roll and acting to urge the cigarette downwardly as the slide is advanced to the position of Figure 5.

It will be appreciated from Figures 4 and 5 that the edges 38 of the knives 31 are angled so that as the length of cigarette form 18 is advanced through the cutting device from Figures 4 to 5 a cut of progressively increasing depth is made until the complete severance of the form 18 into the individual cigarettes, which are collected in the chamber 39.

The result is a very precise clean cut which would not be provided if the knife edges were arranged perpendicular to the travel of the slide.

The component 1 is simply seated on the block 6 and is shown with rubber feet or knobs 40 which frictionally grip the walls 4 and 5 to firmly hold this component in position on the cutting component 2. It will be appreciated however that the cutting component may be utilized with any device for rolling a cigarette form of extended length.

To prevent the slide 35 from pulling free when withdrawn to the position of Figure 4 pivotal lock bars 41 are secured to the ends of the arms 34 and are swung transversely of the arms when it is desired to lock the slide in position and into alignment with the arms when it is desired to free the slide.

The modified form of the invention shown in Figures 8 to 11 shows the cutting component 2' of similar form to the component 2 but provided with a longitudinal block 42 in place of the sliding blocks 23. This block 42 is provided at uniformly spaced intervals with saw cuts 43

defining an angled bottom bearing surface 44, Figures 8 and 9. Into the cuts 43 are inserted the holders 45 formed of spring metal to grip a razor blade 46.

These holders 45 present a lateral flange 47 adapted to bear on the upper surface of the block 42 with the angled edge 48 of the holder bearing on the bottom 44 of the saw cut.

A slide 49 having arms 50 received in the end guides 51 and provided with the slots 52 registering with the blades 46 carry the cigarette form 18 through the cutting mechanism as illustrated in Figures 8 and 9. Suitable pins 53 through the ends of the arms 50 retain the slide against accidental removal.

Again, as will be seen from Figure 9, movement of the slide effects a cutting of progressively increasing depth to give an extremely precise clean cut as desired.

The result of the present invention is that with a substantially continuous operation cigarettes having a machine-made appearance can be quickly formed in a very short interval with simplicity and convenience.

What we claim as our invention is:

In a device for cutting a cigarette form of extended length into individual cigarettes comprising a supporting structure having a pair of longitudinal guides, a plurality of clamping blocks slidably arranged between said guides, stop means at the ends of said guides, expanding means intermediate the length of said guides and between a pair of adjacent blocks to force blocks on opposite sides thereof in opposite directions towards the ends of said guides, a plurality of cutting elements arranged between said clamping blocks and gripped thereby upon expanding of said expanding means, said cutting elements presenting an array of parallel cutting edges above said blocks and spaced the distance of the desired length of individual cigarette, and a cigarette carrying slide movable in a direction parallel said cutting edges and immediately above said blocks to convey a cigarette form of extended length against said knife edges to be cut thereby, said expanding means comprising a rod arranged between said blocks and transverse of said guides and formed with a threaded end, a spring metal band of substantial width of elongated oval form having said rod threaded through the central part and the ends of said band, said band engaging a stop remote from said threaded rod end, and a nut engaging said band to compress same against said stop to expand same outwardly into contact with adjacent blocks on opposite sides thereof.
